UNITED STATES PATENT OFFICE.

RAYMOND N. EHRHART, OF PITTSBURGH, PENNSYLVANIA, ASSIGNOR TO ELLIOTT COMPANY, OF PITTSBURGH, PENNSYLVANIA, A CORPORATION OF PENNSYLVANIA.

SYSTEM FOR REMOVING AIR AND GASES FROM WATER.

1,401,101.

Specification of Letters Patent. Patented Dec. 20, 1921.

Application filed June 5, 1920. Serial No. 386,835.

To all whom it may concern:

Be it known that I, RAYMOND N. EHRHART, a citizen of the United States, residing at Pittsburgh, Allegheny county, Pennsylvania, have invented a new and useful Improvement in Systems for Removing Air and Gases from Water, of which the following is a full, clear, and exact description, reference being had to the accompanying drawings, in which:—

Figure 1 is a diagrammatic section illustrating one form of my invention, and

Fig. 2 is a diagrammatic elevation, partly broken away, illustrating another form of my invention.

My invention has relation to apparatus for treatment of water and other liquids, and relates generally to means for removing air and gases from the water in the manner described and claimed in a patent to William S. Elliott No. 1,321,999, dated November 18, 1919. The method described and claimed in said patent comprises a heater for heating the water to be treated, an evaporator into which the heated water is discharged and in which a pressure is maintained lower than the pressure corresponding to the temperature of the water immediately prior to its entering the evaporator, whereby an explosive boiling action takes place in the evaporator, and a condenser through which the vapors and gases from the evaporator are passed, the water used as the condensing medium passing from the condenser to the heater.

In the said patent the condenser illustrated and described is of the surface type. In that system, the total withdrawal of air is made from the surface condenser, such withdrawal taking place after the feed-water has traversed through the system to the evaporator.

The object of the present invention is to provide means of efficient character whereby a portion of the air may be withdrawn from the feed-water before it enters the heater, thereby reducing the amount of air to be removed by the evaporator.

A further object of the invention is to provide method and means of this character which will operate to simultaneously withdraw air from the water entering the condenser and also from the steam leaving the evaporator.

I have discovered that by using an open

type condenser of the jet or barometric form, these objects may be readily and effectively carried out.

Referring first to Fig. 1 of the accompanying drawings in which I have shown a preferred embodiment of my invention, the numeral 2 designates a heater of the general form described in said Patent No. 1,321,999, 3 the connection for supplying exhaust steam to the heater, 4 an evaporator and 5 a pump or other suitable means for withdrawing the treated water from the evaporator.

6 designates a water supply pipe which delivers water into the condensing chamber of a condenser 7 of the barometric type, this condenser having its tail pipe 8 discharging into the well or container 9 which, in turn, discharges into the heater 2. 10 designates a pipe connection leading from the evaporating chamber of the evaporator 4 into the condenser 7; and 11 designates exhausting means, such as a steam ejector, connected to the condensing chamber of the condenser and which, as will be seen, is arranged to act to simultaneously remove air from the water coming into the condenser by way of the pipe 6 and also from the steam and vapors coming into the condenser through the pipe 10 from the evaporator.

In using this type of condenser, the distance *a* should be great enough to counterbalance the difference between atmospheric pressure and the pressure in the condenser.

Instead of using a barometric condenser, as shown in Fig. 1, I may use a condenser 90 of the low level jet type, such as shown at 12 in Fig. 2. In this case, it is necessary to provide means such as a pump 13 for elevating the water from the condenser into the heater. The other parts shown in this figure corresponding to similar parts in Fig. 1 are given the same reference numerals with the letter "a" affixed.

The advantages of my invention will be apparent since it will be readily seen that by removing as much air as possible from the water entering the system, the duty thrown on the evaporator is greatly reduced, inasmuch as the evaporator does not have the same air content to deal with.

A further advantage of the invention consists in the fact that by the same operation which removes air and other dissolvable gases from the liquid, the temperature of the liquid is raised. This is effected with the

loss of very little energy, since the exhaust steam may be used as the heating medium and a large portion of the heat losses which would otherwise be due to the drop in temperature in the evaporator is recovered in the condenser which acts as a heat exchanger.

It will be understood that the arrangements which I have shown are illustrative only and that the invention may be carried out in various other ways.

I claim:

1. In the treatment of liquids for heating the same and for the removal of air and gases therefrom, the method which consists in introducing the liquid to be treated into an evaporator in which a pressure is maintained lower than the pressure corresponding to the temperature of the liquid before it enters the evaporator, passing the vapors from the evaporator through a condenser, and simultaneously withdrawing air from the liquid entering the condenser and passing therethrough to a heater, and from the steam coming from the evaporator and heating the liquid in said heater, substantially as described.

2. Apparatus for treating liquids for heating the same and for the removal of air and gases therefrom, comprising a heater, an evaporator connected with the discharge of the heater, a condenser connected with the gas and vapor offtake of the evaporator, a water supply connection for the condenser, and means which act simultaneously upon the water as it enters the condenser and upon the vapors leaving the evaporator to extract air and other non-condensable gases therefrom, substantially as described.

3. Apparatus for treating liquids for heating the same and for the removal of air and gases therefrom, comprising a heater, an evaporator, a condenser connected with the evaporator to receive the gas and vapors therefrom and through which the liquid supply for the heater and evaporator passes, and means connected to the condenser for withdrawing therefrom a portion of the air contained in the liquid passing through the condenser, substantially as described.

In testimony whereof, I have hereunto set my hand.

RAYMOND N. EHRHART.
